(57) **CLAIM**

The ornamental design for a display panel for an informational display, as shown and described.

DESCRIPTION

FIG. 1 is a front, top and right side perspective view of an information display for railroads, showing our new design;
FIG. 2 is a front elevational view thereof;
FIG. 3 is a rear elevational view thereof;
FIG. 4 is a right side elevational view thereof; and,
FIG. 5 is a top plan view thereof.
The broken lines represent a display panel and form no part of the claimed design.
